Primary Examiner—Wallace R. Burke*Assistant Examiner*—Holly Bayham[57] **CLAIM**

The ornamental design for an adjustable picture hook unit, as shown and described.

DESCRIPTION

FIG. 1 is an exploded perspective view of the adjustable picture hook unit showing my new design;

FIG. 2 is a perspective view of the rear of the receiving bracket of the adjustable picture hook unit;

FIG. 3 is the front elevational view of the receiving bracket of the adjustable picture hook unit;

FIG. 4 is the rear elevational view of the receiving bracket of the adjustable picture hook unit;

FIG. 5 is a sectional view of the receiving bracket of the adjustable picture hook;

FIG. 6 is a top view of FIG. 3;

FIG. 7 is the rear elevational view of the adjustable picture hook unit;

FIG. 8 is a front elevational view of the adjustable picture hook unit; and,

FIG. 9 is the side elevational view of the adjustable picture hook unit, the side opposite being a mirror image.

The broken line showing of structure is for illustrative purposes only and forms no part of the claimed design.
